(57) CLAIM

The ornamental design for an upper garment, as shown and described.

DESCRIPTION

FIG. 1 is a front perspective view of an upper garment;

FIG. 2 is a front elevation thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines shown in the drawings depict the bounds of the upper garment and forms no part of the claimed invention.

1 Claim, 4 Drawing Sheets
